FEEDING APPLIANCE

Bancroft Hill, Baltimore, Md.

Application July 11, 1949, Serial No. 103,983

3 Claims. (Cl. 65—12)

1

The present invention relates to a device for aiding certain handicapped persons who have had the misfortune of losing a limb, or losing the use of one or more limb members.

In many cases, a party loses the use of one side of the body including one arm and one leg, but retains at least some use of the other arm and leg or the party may lose the use of a hand or arm only and it is for this general group that the present invention has been particularly developed.

In order to operate the device it is necessary that the patient have at least one hand and preferably one foot he can use. The machine is designed to be operated either by one hand or one hand and one foot and can be easily converted to either form, depending upon the requirements of the individual.

The principal object of the invention is to provide a device of this character which is helpful to certain handicapped individuals in handling materials and objects, and at the same time furnish therapeutic aid through the useful use of their limbs.

A further object of the invention is to provide a device of this nature that may have many modifications which can be adapted to a great number of uses and applications to fit the particular case to be treated.

Another object of the invention is to provide a device that is economical to manufacture, practical and simple in its operation in order that those in need of such a device may be both able to acquire and operate.

While several objects of the invention have been specifically pointed out, other objects, uses and advantages will be apparent as the nature of the invention is more fully disclosed, which consists in the novel construction, combination and arrangement of parts shown in the accompanying drawings and described in the following detailed description and in which:

Figure 1 is a top plan view of the apparatus.

Figure 2 is a vertical side view of the same.

Figure 3 is a sectional view taken along the line 3—3 of Figure 2.

Figure 4 is a top plan view of a modified form of the apparatus.

Figure 5 is a vertical side view of the same.

Figure 6 is a view showing a further modified form of the device.

Figure 7 is a sectional view taken along the line 7—7 of Figure 6.

Figure 8 is a view showing still another slightly modified form of the device.

2

Figure 9 is a sectional view taken along the line 9—9 of Figure 8.

Figure 10 is a view in elevation of a bracket for mounting the balancing pan or platform parallel to a predetermined plane.

Figure 11 is a sectional view taken along 11—11 of Figure 10.

Figure 12 is a top plan view of an attachment for the device and Figure 13 is a vertical side view of the same.

Figure 14 is a vertical end view of one of the said aid elements.

Figure 15 is a vertical side view of the same.

Figure 16 is a view in elevation of another type 15 of aid element in the form of a pair of pliers, or pliers.

In referring to the apparatus like reference characters will be used throughout the several views to indicate like and similar parts when 20 practical.

The apparatus consists primarily of a base member 20, a movable arm 22 and means for pivotably supporting the arm upon the base. The arm supporting means consists of a standard 25 24 extending upwardly from the upper surface of the base, which is provided with a hinge 26 at the upper end thereof to which the arm is pivotably attached. The hinge 26 may either be a separate member, or made as a part of the standard 24 and the arm 22. The arm is adapted to

30 swing through a predetermined arc as indicated in Figure 2. Located upon the base and in a vertical plane parallel with the plane formed by the path of the pivoted arm 22, is a second stand-

ard 27, the purpose of which is to carry a mechanism for moving the outer end of the arm in one direction, which in this particular case is upwardly to a predetermined position as indicated by the dotted lines 22' in Figure 2. The arm 22

35 is moved in the opposite direction or downwardly by a cord 28 which is attached to the arm, the length of which is adjustable around the bracket 29. The cord 28 is placed outwardly as near as

40 practical to the outer movable end of the arm 22 which will give as much mechanical advantage as possible in operating the device. The cord is shown as being definitely positioned by passing it through a hole 30 within the arm and securing the same about the bracket 29.

45 The mechanism for moving the arm 22 upwardly consists of a secondary arm 32 which is hinged on the upper end of the support 27 and having its axis parallel with the axis of the hinge

50 34. The arm 32 extends beyond the hinge 34 and is shown as portion 32'. Secured to the outer

55

end of the arm portion 32 is a small roller 34 adapted to contact the under side of the arm 22. The opposite end of the arm 32' is provided with a platform or base 36. The platform is designed to receive a number of weights 38 for moving the arm 22 upwardly. It is preferable to carry the platform 36 in a horizontal position, therefore the platform is hinged adjacent its bottom at the outer end of the arm 32' by the hinge 40. A bar or arm 42 is pivotably connected with the platform 36 by the bracket 44, and to a bracket 46 carried by the standard 27. The bar 42 is of substantially the same length as the arm portion 32'. By vertically placing the bar 42 above the bar 32' and having the distance between their pivots to platform 36 equal to the distance of the pivotal connection of the arm 42 with the bracket 46 above the pivotal connection of bar 32' with the bracket 46 will operate to maintain the platform in a horizontal plane as it moves up and down with the bar or arm member 32'. The movement of the secondary arm 32 and 32' may be regulated by the arcuate arms 48 and 49 which pass through the standard 27 as shown in Figure 3 by inserting pin 50 in one or another of the holes 51 carried by the arms 48 and 49. As the arm 32' is always being urged downwardly by the weights 38 the pin 50 will determine the movement of the arm portion 32 which in turn will regulate the height of the arm 22.

The platform 36 is removably and pivotably secured to the outer end of the arm portion 32' by the threaded rod 52 and the wing nut 53. The bracket 46 is also removable and may be moved to the opposite end of the hinge 31. By this arrangement the platform may be moved to either side of the arm 22 to accommodate right and left hand individuals.

The outer end of the arm 22 is formed to receive a number of aid elements, one of such elements is shown in Figures 1 and 2 for holding the pages of a book open for reading, or copying extracts therefrom. This member is connected with the arm 22 by the member 56' which is in turn connected with the end engaging means 58. The member 58 is of such form as to engage the end of the arm 22 and be secured thereto by a pin 60.

Another form of aid element is shown in Figures 4 and 5 and is in the form of a fork 67 for holding particles of food, such as meats, for cutting the same; for example, if the individuals can hold the particle of food in a fixed place they are able to use one hand in cutting and by elevating the arm 22 the particle may be removed from the fork 67.

It is not necessary, or desirable to have the device always permanently attached to the table, or other supporting member 62. Therefore, for securing purposes a hingeable clamp member 64 is preferred, however, any other practical and convenient means may be used. This particular clamp is adapted to be carried by the support 62 and may be slidably secured within a flanged groove as shown in Figures 2 and 3 at 66, or secured by screws as shown at 68. Either form is provided with a hinge 69 and a hand screw 70 for contacting the upper surface of the base member 20. It can be seen that when the clamp is not in use the upper arm may be swung out of the way from over the top of the table 62.

Figures 1 and 2 show a hand and foot operated type, while in Figures 4 and 5 only a hand-operated type is shown.

For operating the hand and foot type the cord 75 at an angle to the plane of the moving arm 22

28 extends below the support 62 to either a pedal or a loop formed in the cord (not shown) which is engaged by the foot of the individual. The position of the arm 22 is normally that as shown at 22' being held in that position by the weights 38 carried by the platform 36. When a downward pull is exerted on the cord 28 by the foot the arm 22 moves downwardly, therefore, the aid element attached to the outer end of the arm will also move downwardly to cause the aid element to perform its particular function.

Referring now in particular to Figures 4 and 5, which is the hand operated type, the device is broadly the same as just described for the form shown in Figures 1 and 2 except for the operating means. For operating this type there is provided a hand lever 80 mounted upon the base 20. The lever is pivoted at a convenient point 81 and is adapted to rock upon the pivot in order to get a slight up and down motion for the lever. The lever is provided with a pin 82 for engaging a plurality of stationary apertures 83 located in, or carried by, the base. The inner end of the lever is provided with means, such as a hole 84, for securing one end of the cord 28 to the lever. The cord is secured to the arm 22 as previously described and extends around a pulley 86 and through an appropriate opening 33 within the lower end of the support 27 to the inner end of the lever. By moving the lever about the pivot 81 the arm 22 is drawn downwardly against that force caused by the weights carried by the platform 36. To move the lever, the outer end 80' is slightly raised to disengage the pin 82 from one of the apertures 83 and moved to the desired point where it may be lowered in order that the pin 82 may again engage an appropriate aperture and hold the arm 22 in the desired position.

The base may carry a recess as shown at 90 in Figures 1, 2, and 3, and at 91 in Figures 4 and 5, for receiving a gripping element which is specifically shown in Figures 12 and 13. This element consists of a plurality of rectangular blocks 92, the center pair having an elliptical opening 93 which is used to receive most any shaped object such as a bottle of ink or the like. These blocks are assembled to slide within an open top box member 94. One end of the box is provided with a thumb screw 95 which is adapted to contact the near block and press them together. The blocks are of different thicknesses which will enable the user to adjust the size of the gripping opening 93 for various sizes of objects.

While a specific type of mechanism has been shown and described for automatically furnishing a constant force for urging the bar in one direction, which is normally upward, other suitable mechanisms may be used as shown in Figures 6 to 9.

Referring to Figures 6 and 7, the arm 22 is moved by appropriate weights 96. These weights are supported by a cord 97 which has one end connected with the arm 22 at 98 and extending up and over a pulley 99 to a weight carrying member 100. The pulley is supported upon a standard 102 which is positioned adjacent the arm 22. The arm is provided with a plurality of apertures 104, into which a pin 106 may be inserted to limit the movement of the arm through a predetermined prescribed arc. The weights 96 are of such a nature that they can be added or removed as desired. The pulley 99 is arranged

in order to pick up the cord 97 from a point over the arm and allow the weights 96 to be supported to one side of the arm. The hand and foot operating means for this modification are substantially the same as previously described.

In Figures 8 and 9 there is shown a still further modification of the constant urging means in the form of a coiled spring 108, which is carried within a slotted tube, or sleeve 110. The lower end of the tube is fixably secured to the base, the upper end being provided with a plurality of apertures 112, through which a pin 114 is inserted at different levels for regulating the height of the arm 22 in substantially the same manner as described for Figures 6 and 7.

In Figures 14, 15 and 16 there are shown several other types of aid elements. In Figures 14 and 15 is another type of clamping element for holding objects in a horizontal position. This element consists of a base 116 having blocks 118 and 120 which are provided with a V or U-shaped upper surface 122 and separated by a center piece 124. To cooperate with this bottom portion is an upper portion which consists of similarly shaped, single inverted block 126, a shaft 128 and a fixture 130 which is adapted to fit over the outer end of the arm 22.

In Figure 16 there is shown still another form of aid element. In this modification there is shown a pair of pliers 132. One of the handles is connected by a detachable member 136 to a member 138 which is adapted to be attached to the end of the arm 22. The other handle of the pliers is detachably attached to a base plate 140 and is held by a suitable pin 142. By attaching the member 138 to the outer end of the arm 22 and resting the base 140 upon a table or support 20 the pliers may be caused to open and close by operating the arm 22.

The device has been shown in various ways all of which involve the same general principle and while the device has been specifically illustrated it is not intended that this should be a limitation as various changes in detail may be made without departing from the spirit of the invention and the scope of the invention is best defined in the appended claims.

I claim:

1. A feeding appliance comprising a base adapted to rest upon a horizontal support, an arm having one end hingedly connected with the base, means located between the hinged end of the arm and the outer end thereof for normally urging the outer end of the arm upwardly and away from the horizontal plane of the support and means for regulating the force of the said urging means,

means connected with the said arm for moving the same toward the horizontal plane of the support, means for predetermining the arc through which the arm is operated and means opposite the hinged end of the arm for releasably attaching an aid element.

2. A feeding appliance consisting of an arm hinged at one end thereof and means for holding said hinged end in a fixed location, the opposite outer end of the arm adapted to swing about a predetermined arc above a horizontal plane, means for constantly urging the opposite end of the arm upwardly through said arc consisting of a pivoted lever one end of which is adapted to contact the under side of the arm and the opposite end beyond the pivot adapted to receive a force for rotating the lever about the pivot for moving the said arm, a manually operated means for moving the arm in the opposite direction through said arc, a plurality of detachable aid elements adapted to be received upon the outer end of the arm.

3. A feeding appliance comprising a base, an arm having one end hingedly carried by the base, means for resiliently supporting the opposite end of the arm within a pre-determined arc, manually operable means for rotating the arm about its hinged end against the resilient support, consisting of a hand lever and means for connecting the movable end of the arm with the lever, a plurality of stops associated with the said lever for limiting the movement of the lever and the arm through the arc, the outer end of the arm being adapted to receive an aid element.
